DEFENSIVE PUBLICATION

UNITED STATES PATENT AND TRADEMARK OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

Continuation of application Ser. No. 208,547, Dec. 16,
1971. This application June 7, 1974, Ser. No. 477,373.

Int. Cl. G06F 7/06

U.S. Cl. 340—172.5

41 Sheets Drawing. 6 Pages Specification

A process is disclosed for the sequential recovery of the records of a file wherein the records are randomly located on a storage device which comprises a plurality of areas. The process is based upon the principle that the recovery

of the records in sequence order is isomorphic to the distribution of the sequence of records into the specific locations on the storage device. In the process, a directory is employed which contains the tags of the records in se-

quential order of key value, the tag comprising the records key value, and its address in the storage device. Utilizing the directory, a simulation of the distribution of the tags therein is performed and the result of the simulated distribution is written out in the form of a string of items which includes portions of the tags grouped therein according to areas and information as to which records and how many are to be written out at respective visits to the storage device. The items in the string are then employed in the reverse order of their writing out to determine the recovery or retrieval of the records in sequential order of key value. In one aspect of the invention, the record recovery may be performed by scanning the areas of the storage device in a cyclic fashion. In another aspect, the record recovery may be achieved by selectively visiting chosen areas of the storage device, the determination of the selection of the area which may be visited at a particular juncture depending upon predetermined criteria such as quantity of records that can be written out at a visit, etc. The process can be accomplished either by a single or multi-pass operation. The process is a substantial improvement over other sequential record recovery processes which employ a tag sort and utilize the sorted tags to perform an ordered record retrieval by conventional methods. In another aspect of the invention, order substrings of the file are formed and these substrings then function as the areas in the execution of the process. Concurrently, with the formation of these strings, corresponding directories are created which can subsequently be merged.
